(57) CLAIM

The ornamental design for a griddle pan, as shown and described.

DESCRIPTION

FIG. 1 is a top perspective view of a griddle pan, showing my new design;

FIG. 2 is a bottom perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a front elevation view thereof;

FIG. 8 is a rear elevation view thereof; and,

FIG. 9 is a cross sectional view thereof taken from FIG. 4. The article is shown with a symbolic break in its length. The appearance of any portion of the article between the break lines forms no part of the claimed design.
